RAM CONSTRUCTION

Alfred J. Ersted, Atherton, Calif.

Application October 12, 1946, Serial No. 703,011

15 Claims. (Cl. 223—39)

1 The present invention relates to a ram construction for bag turning machines.

One object of the present invention is to provide a ram construction which is simple in design, inexpensive to manufacture and highly efficient in operation.

Another object is to provide a ram construction which is extremely quiet in operation.

Another object is to provide a ram construction which is readily adjustable to any bag and which may be accurately adjusted during operation.

Another object is to provide a ram construction which automatically signals insufficient lubrication thereof.

Other and further objects and advantages of the present invention will become apparent from the following description and drawings in which:

Fig. 1 is a plan view of the ram construction of the present invention illustrating the ram in its retracted position.

Fig. 2 is a plan view similar to Fig. 1 showing the ram in its forward and expanded position, certain portions being broken away.

Fig. 3 is a longitudinal section of the ram structure shown in Fig. 1 taken along line 3—3 thereof.

Fig. 4 is an enlarged transverse section of the ram structure taken along line 4—4 of Fig. 1.

Fig. 5 is an enlarged section of a portion of Fig. 1 taken along line 5—5 thereof, certain part being shown in elevation.

Fig. 6 is an enlarged longitudinal section of the crosshead of the ram structure taken along line 6—6 of Fig. 1.

Fig. 7 is an enlarged section taken along line 7—7 of Fig. 1.

Fig. 8 is an enlarged longitudinal section of the front end of one of the ram guide rods taken along line 8—8 of Fig. 1.

Fig. 9 is an enlarged section of a portion of Fig. 1 taken along line 9—9 thereof, certain parts being omitted.

Fig. 10 is an enlarged transverse section of a portion of the ram structure taken along line 10—10 of Fig. 1.

The ram structure of the present invention is adapted for use in connection with bag turning machines of the type as shown in Patent No. 2,295,940 issued Sept. 15, 1942, to A. J. Ersted. It being understood however that its use is not limited to the particular type of bag turning machine referred to herein since it may be advantageously used in connection with various other

types of bag turning machines as will be obvious to those skilled in the art.

Referring now to the drawings and especially Figs. 1 and 3 thereof, 1 designates the frame structure of a bag turning machine provided with a rectangular opening 2. The entire ram structure 3 of the present invention is mounted on the frame structure 1 above the opening 2 so as to facilitate the connection thereof with the drive mechanism of the bag turning machine in the manner as disclosed in the patent above referred to.

The ram construction (Figs. 1, 2, 3 and 6) comprises a crosshead 6 including a sleeve bearing 7 provided with a lug 8 within which a crosshead rod 9 is fixed. The rod 9 is transversely disposed with respect to the longitudinal axis of the sleeve bearing 7 and projects a considerable distance from the lug 6 at either side thereof.

20 The sleeve bearing 7 is slidably mounted upon a crosshead supporting and guide rod 11 the reduced rear end 12 of which is slidably disposed within a bore 13 of a supporting bar 14 rigidly secured in spaced relation to the frame 1 of the bag turning machine by means of bolts 15 and spacing sleeves 16 (Figs. 3 and 6). The front end 17 of the crosshead supporting rod 11 is of reduced diameter (Fig. 5) and slidably disposed within a bore 18 of a bearing block 19 firmly secured to the frame 1 by means of cap screws 21. Disposed intermediate the bearing block 19 and a shoulder 22 of the rod 11 and surrounding the reduced portion 17 thereof is a coil spring 23 for normally holding the supporting rod 11 in position against sliding movement relative to the bearing block 19 and supporting bar 14 and with the shoulder 24 of the rod in abutment with the supporting bar 14 (Fig. 6).

25 The sleeve bearing 7 of the crosshead 6 is further provided with a lug 31 (Fig. 6) at the lower side thereof to which a pitman 32 is pivotally connected by means of a yoke 33 and pivot pin 34. The pitman 32 is in turn pivotally connected to the actuating mechanism of the bag turning machine such as for instance disclosed in the Ersted Patent 2,295,940, previously referred to herein.

30 Disposed adjacent the crosshead supporting rod 11 are ram supporting and guide rods 36 and 37 (Figs. 1, 2 and 3). The rear end of the ram guide rod 37 (Fig. 7) is slidably received within a bore 38 of a yoke 39 which in turn is pivotally connected by pivot pin 40 to the supporting bar 14, while the rear end of the guide rod 36 is slidably disposed in the bore 41 of a yoke 42 in turn pivotally connected by a pivot pin 43 to the bar

14. Each of the pivot pins 40 and 43 is held against upward movement by a cotter pin 44 (Figs 3 and 7) while downward movement of these pins is prevented by the frame 1. Consequently, both pins are securely held in place against accidental removal thereof.

The front end of the ram guide rod 37 (Figs. 1, 2 and 8) is slidably arranged in a bore 51 of a yoke 52 pivotally secured by means of a pivot pin 53 to a square nut or block 54 provided with a threaded bore within which an adjustment screw 55 is disposed. The front end of the rod 37 is provided with a bore 56 (Fig. 8) and disposed within the same intermediate the rod 31 and the square nut or adjustment block 54 is a coil spring 57 which normally prevents sliding movement of the rod 37 relative to the yoke 52 and block 54 as well as the yoke 39 and bar 14 and normally holds the rear end of the rod 37 in engagement with the bar 14.

The front end of the rod 36 (Figs. 1, 2 and 9) is slidably disposed in a yoke 61 which is pivotally secured by means of a pivot pin 62 to a square nut or adjusting block 63 threaded upon the adjusting screw 55, while a coil spring 64 is arranged in a bore 65 in the front end of rod 36 and disposed intermediate the same and block 63 normally prevents sliding movement of the rod 36 relative to the yokes 61 and 42 and holds the rod 36 in engagement with the bar 14.

The adjustment screw 55 (Figs. 1 and 2) is rotatably supported in the bearing block 19, previously referred to, and bearings 68 and 69 secured by means of cap screws 70 to the frame 1. One end of the adjustment screw 55 extends beyond the bearing 69 and keyed to the same is a crank handle 71 for permitting rotation of the screw in one or the other direction. The adjustment screw 55 is provided with two threaded portions 72 and 73 provided with a left and right hand thread, respectively. The square nut 54 is disposed on the threaded portion 72 and the square nut 63 is disposed on the threaded portion 73 so that upon rotation of the crank handle 71, the nuts 54 and 63 may be moved toward or away from each other whereby a corresponding movement of the front end of the ram guide rods 36 and 37 is effected. The rods 36 and 37 are angularly disposed with respect to each other and by turning the crank handle 71, the angular disposition of the ram guide rods 36 and 37, relative to each other may be increased or reduced as desired.

Sufficient space between the front ends of the rods 36 and 37 and blocks 63 and 54 is provided and sufficient bearing surface of the rods within the yokes 61 and 52 is established to permit relative movement of the rods with respect to their yokes 61 and 52 as the distance between yokes 61, 42 and 52, 39 is reduced or increased during pivotal movement of the rods 36 and 37 about pivot pins 43 and 49, respectively.

A calibrated scale 75, attached to or forming an integral part of the bearing 69 and extending parallel to the screw 55, cooperating with a pointer on line 76 on the yoke 52 is provided to facilitate adjustment of the ram guide rod to a predetermined position.

Slidably mounted upon each ram guide rod 36 and 37 (Figs. 1, 2 and 7) are long ram bearings 78 and 79 of sleeve like configuration. Each bearing 78 and 79 comprises a lug 80 to which a transverse bearing 81 is pivotally connected by means of a pivot pin 82. Each transverse bearing 81 is slidably positioned upon the transverse

rod 9, previously referred to, so that upon reciprocation of the crosshead 6 by the pitman 32 during the operation of the bag turning machine the bearings 78 and 79 are reciprocated therewith and are caused to slide along the ram guide rods 36 and 37 in diverging paths during the forward stroke of the crosshead 6 and in converging paths during the backward stroke thereof.

Since the bearings 81 are slidable on the cross rod 9 they are free to shift laterally on the rod 9 according to the diverging or converging paths of travel of the bearings 78 and 79. Furthermore, the pivotal connection between the bearings 81 and bearings 78 and 79 permit the angular adjustment between the rods 36 and 37 without any binding between these bearings during the operation of the mechanism.

Attached to the bearings 78 and 79 for reciprocation therewith is a ram unit 91, comprising a section 92 secured to the bearing 78 and a section 93 secured to the bearing 79. Each ram section comprises an inner and an outer ram rod 95 and 96, respectively, provided at their front ends with a ram head 97.

The rear portions 101 and 102 of the ram rods 95 and 96 are disposed adjacent and parallel to each other and are mounted within and welded to supporting bars 103 and 104 in turn secured by cap screws 105 to pads 106 (Figs. 3, 7 and 10) provided on and forming an integral part of the ram bearings 78 and 79, respectively. The front portions 107 and 108 of the ram rods 95 and 96 are angularly disposed relative to each other and the portions 107 of the inner ram rods 95 are disposed parallel to the ram guide rods 36 and 37, respectively.

The portions 107 and 108 of the ram rods 95 and 96 of each ram section 92 and 93 are slidably supported within guides 110 and 111, respectively. The guide 110 is connected by means of cap screws 112 to the yoke 61 and the guide 111 is connected by means of cap screws 113 to the yoke 52.

Each guide 110 and 111 (Fig. 4) comprises an upper strap 115, a lower strap 116, a guide block 117 held in place by the cap screws 112 or 113, respectively, and a guide roller 119 rotatably mounted between the straps 115 and 116 in spaced relation to the guide block 117 by means of a bolt 120. The ram portions 92 and 93 are disposed within the guides 110 and 111, respectively, in such a manner that the portions 107 of the inner ram rods 95 contact the rollers 119 and are guided thereby while the outer ram rods 96 of both ram sections 92 and 93 contact and are guided by the guide blocks 117 when the ram 91 is disposed in its rearmost or fully contracted position (Fig. 1). When the ram 91 is in its fully expanded and extreme forward position (Fig. 2) the ram rods 107 and 108 are out of engagement with the guide blocks 117 and guide rolls 119.

The straps of the guides 110 and 111 support the ram sections 92 and 93 in vertical direction, as best seen from Fig. 4, and effectively eliminate vertical whip of the ram sections.

All of the bearings 7, 79, 78 and 81 are provided with oil wells 125 within which oil retaining felt pads are disposed to assure an even and continuous lubrication of the bearing surfaces during operation.

From the above it is therefore apparent that during the operation of the bag turning machine in connection with which the ram construction of the present invention is employed, the ram 91 is reciprocated to thereby effect in association

with other parts of the machine the turning of the bags presented thereto in the same manner as specifically explained in my prior patent above referred to. If it is desired to change the width of the ram i. e. the spacing between the ram sections 92 and 93 and the degree of expansion and contraction of the ram the operator turns the crank handle 71 in one or the other direction whereby the nuts 54 and 63 are shifted toward or away from each other and a corresponding adjustment of the ram guide rods 36 and 37 and ram sections 92 and 93 with respect to each other is obtained. In this way the ram may be quickly and easily adjusted to any desired width of bags without stopping the operation of the machine which heretofore has been necessary. Since the operator can observe and change the degree of adjustment while the ram is in operation a nicety of adjustment can be accomplished which heretofore could not be obtained except by a laborious trial and error procedure and continuous starting and stopping of the machine.

During the initial phase and a substantial part of the forward stroke of the ram, the ram sections 92 and 93 are firmly guided by the guide rolls 118 contacting the portions 107 of the inner guide rods 95 so that inward yielding of the ram sections during the initial phase of the bag turning operation, especially when bags of heavy material are handled, is prevented.

Due to the provision of large and efficient bearing surfaces and the arrangement of all parts of the structure in such a manner as to almost entirely eliminate all undesirable stresses and bending forces a very quiet operation of the ram structure is obtained.

It should further be noted that the crosshead guide rod 11 and ram guide rods 36 and 37 are normally held in their rearmost positions by springs 23, 57 and 64, respectively, but may be slightly shifted forward in their supports if the springs are compressed. Therefore if the attendant of the machine neglects to lubricate the bearings 7, 78 and 79 and the oil wells 125 thereof run dry, the increased friction overcomes the force of the springs 23, 57 and 64 and the guide rods 11, 36 and 37 shift back and forth during the reciprocation of the ram causing a chattering noise which warns the attendant to lubricate the mechanism before any damage has been done to the moving parts thereof.

The assembly and disassembly of the mechanism is extremely simple. Practically the entire mechanism can be disassembled by removing the bar 14 and pivot pin 33.

Irrespective of the manifold advantages of the present ram construction the same is of rigid construction to withstand the continuous wear to which high speed bag turning machines are subjected in commercial use.

While I have described a particular embodiment of the present invention, it will be understood however that various changes and modifications may be made in the details thereof without departing from the spirit and scope of the appended claims.

Having thus described my invention, what I claim as new and desire to protect by Letters Patent is:

1. A ram construction for bag turning machines comprising a ram unit having separate cooperating sections disposed adjacent each other, means angularly disposed relative to each other for guiding said sections for movement in di-

verging paths, means for simultaneously reciprocating said sections along said guiding means to thereby effect lateral expansion and contraction of said ram unit, and means for adjusting the angularity of said guiding means relative to each other to thereby increase or decrease the amount of expansion of the ram unit during reciprocation thereof.

2. A ram construction for bag turning machines comprising a ram unit having separate cooperating sections disposed adjacent each other in spaced relation, guide means angularly disposed relative to each other for slidably supporting said ram sections, means for reciprocating said ram sections on said guide means in diverging paths to thereby effect lateral expansion and contraction of said ram unit, and means for varying the angular disposition of said guide means relative to each other to thereby vary the amount of lateral expansion of the ram unit during reciprocation thereof.

3. A ram construction comprising a ram unit having separate sections, means for guiding said sections for movement in diverging paths, a crosshead slidably disposed intermediate said guiding means, means for pivotally and laterally slidably connecting said ram sections to said crosshead, and means for reciprocating said crosshead to thereby effect reciprocation of said ram sections in diverging paths.

4. A ram construction comprising a ram unit having separate sections disposed in spaced relation adjacent each other, a crosshead, means for guiding said crosshead for reciprocation along a predetermined path, means slidably and pivotally connecting said ram sections to said crosshead for reciprocation therewith, and means for guiding said ram sections in diverging paths to thereby effect expansion and contraction of the ram unit incident to its reciprocation.

5. A ram construction comprising a ram unit having separate sections, means for guiding said sections for movement in diverging paths, a crosshead slidably disposed intermediate said guiding means, means for pivotally and laterally slidably connecting said ram sections to said crosshead, means for reciprocating said crosshead to thereby effect reciprocation of said ram sections in diverging paths, and means for adjusting the guiding means relative to each other for varying the divergence of the paths of travel of said ram sections.

6. A ram construction comprising a ram unit having separate sections disposed in spaced relation adjacent each other, a crosshead, means for guiding said crosshead for reciprocation along a predetermined path, means slidably and pivotally connecting said ram sections to said crosshead for reciprocation therewith, means angularly disposed with respect to each other for guiding said ram sections in diverging paths to thereby effect expansion and contraction of the ram unit incident to its reciprocation, and means for varying the angularity of said last named guiding means to increase or reduce the expansion of said ram unit.

7. A ram construction comprising a ram unit having separate sections, pivotally mounted guide means angularly disposed relative to each other for guiding said sections for movement in diverging paths, means for reciprocating said sections along said guide means to thereby effect lateral movement of said sections toward and away from each other, and means for pivotally moving said guide means relative to each other

to vary the angular disposition of said guide means with respect to each other to thereby change the divergence of the paths of travel of said sections.

8. A ram construction comprising a ram unit having separate ram sections, pivotally mounted guide means disposed in spaced relation adjacent each other, means for pivotally moving said guide means toward or away from each other, means for slidably supporting said ram sections on said guide means, actuating means for reciprocating said sections on said guide means, and means pivotally and laterally slidably connecting said supporting means to said actuating means.

9. A ram construction comprising a ram unit having separate ram sections, pivotally mounted guide means disposed in spaced relation adjacent each other, means for pivotally moving said guide means toward or away from each other, means for slidably supporting said ram sections on said guide means, and actuating means for reciprocating said ram sections on said guide means, said actuating means including a cross-head, means interposed between said guide means for slidably supporting said cross-head, a rod fixed to said cross-head and transversely disposed to said guide means, and means pivotally and laterally slidably connecting said rod with said ram section supporting means.

10. A ram construction comprising a frame, a ram unit, means for slidably supporting said ram unit, means for reciprocating said ram unit on said supporting means, means for slidably mounting said ram unit supporting means on said frame, and means for normally preventing sliding movement of the ram unit supporting means but for permitting sliding movement thereof upon excessive friction between said ram unit supporting means and ram unit during reciprocation of the latter.

11. A ram construction for bag turning machines comprising a ram unit, means for slidably supporting said ram unit, means for slidably mounting said supporting means, means for reciprocating said ram unit on said supporting means, a coil spring intermediate said mounting and said supporting means for normally holding said supporting means stationary on said mounting means upon reciprocation of said ram unit and for permitting reciprocation of said supporting means in said mounting means into and out of contact therewith upon excessive friction between said supporting means and ram unit to thereby create an audible signal.

12. A ram construction for bag turning machines comprising a frame, a ram unit including separate sections disposed in spaced relation adjacent each other, ram guide rods mounted on said frame in spaced and angularly disposed relation, each of said ram sections having a sleeve bearing slidably mounted on one of said rods, a crosshead guide rod intermediate said ram guide rods, a crosshead slidably mounted on the cross-head guide rod, a transverse rod fixed to said crosshead, a transverse bearing associated with each sleeve bearing and pivotally connected thereto, said transverse bearings being slidably mounted upon said transverse rod, and means for reciprocating said crosshead on said crosshead

guide rod to thereby effect reciprocation of said ram sections and lateral movement thereof toward and away from each other.

13. A ram construction for bag turning machines comprising a frame, a ram unit including separate sections disposed in spaced relation adjacent each other, ram guide rods adjustably mounted on said frame in spaced and angularly disposed relation, each of said ram sections having a sleeve bearing slidably mounted on one of said rods, a crosshead guide rod intermediate said ram guide rods, a crosshead slidably mounted on the crosshead guide rod, a transverse rod fixed to said crosshead, a transverse bearing associated with each sleeve bearing and pivotally connected thereto, said transverse bearings being slidably mounted upon said transverse rod, means for reciprocating said crosshead on said crosshead guide rod to thereby effect reciprocation of said ram sections and lateral movement thereof toward and away from each other, and means for adjusting the angularity of the ram guide rods relative to each other to thereby increase or decrease the amount of lateral movement of the ram sections with respect to each other.

14. A ram construction comprising a ram unit having separate sections, guide means angularly disposed relative to each other for guiding said sections for movement in diverging paths, means for reciprocating of said sections along said guide means to thereby effect lateral movement of said sections toward and away from each other incident to their reciprocation, and means for guiding and supporting said ram unit against vertical whip.

15. A ram construction for bag turning machines comprising a frame, a ram unit including sections laterally movable relative to each other, ram guide rods for supporting said sections for sliding movement longitudinally thereof, means for pivotally mounting the rear end of said rods on said frame, an adjustment screw rotatably mounted on said frame having oppositely threaded portions, an adjustment block threadedly mounted on each of said threaded portions, means pivotally mounting the front end of said rods to said blocks, means for reciprocating said ram unit on said ram guide rods, and means for rotating said adjustment screw for shifting said blocks toward or away from each other to effect pivotal movement of the ram guide rods about the pivotal mounting means at the rear ends thereof to thereby dispose said rods in any desired angular position relative to each other.
